UNITED STATES PATENT OFFICE

156,547

MOBILE DINER

George Fred Madison, Duke, Okla.

Application May 7, 1948, Serial No. 146,210

Term of patent 7 years

(Cl. D14—3)

To all whom it may concern:

Be it known that I, George Fred Madison, a citizen of the United States, residing at Duke, in the county of Scioto and State of Oklahoma, have invented a new, original, and ornamental Design for a Mobile Diner, of which the following is a specification, reference being made to the accompanying drawing, forming part thereof.

Figure 1 is a side elevation of a mobile diner showing new design, with the diner in service position.

Figure 2 is a rear elevation of the diner.

Figure 3 is a top plan view of the diner.

Figure 4 is a side elevation of the mobile diner when it is closed to service and ready for traveling.

Figure 5 is a rear elevation of the mobile diner shown in Figure 4.

The sides of the diner opposite those shown in Figures 1 and 4 are similar to those shown in said figures.

I claim:

The ornamental design for a mobile diner, as shown and described.

GEORGE FRED MADISON.
